Primary Examiner — John R Yeh(74) *Attorney, Agent, or Firm* — Perkins Coie LLP(57) **CLAIM**

The ornamental design for a scrubbing device, as shown and described.

DESCRIPTION

FIG. 1 is a perspective view of a scrubbing device.

FIG. 2 is a left view thereof.

FIG. 3 is a right view thereof.

FIG. 4 is a front view thereof.

FIG. 5 is a rear view thereof.

FIG. 6 is a top view thereof; and,

FIG. 7 is a bottom view thereof.

The broken lines in the figures show portions of the scrubbing device and/or environment that form no part of the claimed design.

1 Claim, 5 Drawing Sheets(56)
